UNITED STATES PATENT OFFICE

168,550

BOAT ANCHOR

Olaf H. Johnson, Oakland, Calif.

Application January 30, 1952, Serial No. 18,303

Term of patent 14 years

(Cl. D71—1)

To all whom it may concern:

Be it known that I, Olaf H. Johnson, a citizen of the United States, residing at Oakland, State of California, have invented a new, original, and ornamental Design for a Boat Anchor, of which the following is a specification, reference being had to the accompanying drawings, forming a part hereof, wherein:

Figure 1 is a perspective view of a boat anchor embodying my new design.

Figure 2 is a plan view of the anchor.

Figure 3 is a side elevation of the anchor.

I claim:

The ornamental design for a boat anchor, substantially as shown.

OLAF H. JOHNSON.
